UNITED STATES PATENT OFFICE.

WATSON M. HOLMES, OF HOOSICK FALLS, NEW YORK, ASSIGNOR TO THE PLANTERS COMPRESS COMPANY, OF BOSTON, MASSACHUSETTS.

BALE-STAY BAND.

SPECIFICATION forming part of Letters Patent No. 679,845, dated August 6, 1901.

Application filed January 16, 1901. Serial No. 43,492. (No model.)

To all whom it may concern:

Be it known that I, WATSON M. HOLMES, a citizen of the United States, residing at Hoosick Falls, in the county of Rensselaer and State of New York, have invented a new and useful Bale-Stay Band, of which the following is a specification.

This invention relates to bale-stay bands.

The object of the invention is to provide means for retaining the bale-stays in efficient engaging relation with respect to the bale during the removal of the bale from the press and until the permanent securing wires or devices are applied to the bale.

15 A further object of the invention is to provide a construction and arrangement of bale-stay band, which may be applied without arresting the continuous operation of the press.

20 A further object of the invention is to provide a construction of bale-stay band or similar device which is simple in construction, which may be readily and easily applied, and which is efficient in operation.

Other objects of the invention will appear 25 more fully hereinafter.

The invention consists, substantially, in the construction, combination, location, and arrangement, all as will be more fully herein-after set forth, as shown in the accompanying drawings, and finally pointed out in the appended claims.

Referring to the accompanying drawings and to the various views and reference-signs appearing thereon, Figure 1 is a broken view, 35 in longitudinal section, of a portion of a compressing apparatus, showing bale-detaching devices and stays in position ready for actuation to effect a detachment of the bale and the temporary clamping of the detached bale to 40 the bale-base, the bale-stay band or securing device being shown applied to one of the bale-stays. Fig. 2 is a transverse section on the line 2 2 of Fig. 1 looking in the direction of the arrows. Fig. 3 is a view similar to Fig. 1, the 45 bale-stays being shown projected into the compressed column and the bale-stay band or securing device being shown in applied position. Fig. 4 is a transverse section on the line 4 4 of Fig 1 looking in the direction 50 of the arrows. Fig. 5 is a detached detail view in perspective of the hook portion of

the bale-stay band or securing device. Fig. 6 is a broken detail view, in side elevation, of the part shown in Fig. 5, illustrating the arrangement for securing the bale-stay band 55 or securing device to the hook portion.

The same part is designated by the same reference-sign wherever it occurs throughout the several views.

In patents to George A. Lowry, No. 630,369, 60 issued August 8, 1899, No. 645,728, issued March 20, 1900, and No. 645,734, issued March 20, 1900, are set forth and described a compressing apparatus for compressing fibrous or other material, in which the material is 65 compressed and highly condensed in the form of a constantly-lengthening column of high density. Said patents also disclose means for detaching a suitable length from said compressed column to form a commercial bale, 70 and the application of bale-stays to the detached portion to prevent endwise expansion thereof while said detached portion is being removed from the compressing apparatus and until the permanent wires or other securing 75 devices may be applied thereto. By reason of the tendency of the detached portion to expand endwise it has been found that the bale-stays are liable to be forced out of engaging relation with respect to the end of the 80 detached portion or bale, thereby allowing the bale to expand before the permanent wires have been applied, and in order to avoid this objection it has been usually customary when the bale-stays are projected into the column 85 of compressed material to apply a holding-band around the stays in order to prevent such stays from separating or spreading apart or being forced by the endwise expansion of the bale. The present invention relates particularly to a construction and arrangement for accomplishing this purpose in a most efficient, simple, and expeditious manner, and while applicable for use generally as a bale-stay-securing device it is particularly desirable for use on continuously-running presses, 90 whereby such stay-band or securing device may be applied to the bale-stays without arresting the operation of the press while the bale-stays are being applied and a bale is 95 being detached and removed from the compressing apparatus.

Referring to the accompanying drawings, reference-sign C designates a portion of the compressing apparatus; D, the bale base or support; E, the plunger or ram, and F the bale-stays. These parts may be of the usual or any convenient construction and arrangement, as fully set forth in the patents above referred to, the bale-stays F being arranged to engage at one end with the bale-base D to provide at the opposite end with engaging devices such as knives G, for instance—arranged to be forced or projected into the compressed column of material to grip or clamp between such blades or knives 15 and the bale-base D a length of the compressed column to form a bale, as fully set forth in the patents mentioned.

A designates a forging or casting, to one end of which is secured a stay-band or securing device B, said forging or casting adapted to be detachably engaged with a bale-stay and the stay-band or securing device B adapted to be passed around the bale and in encircling relation with respect to the bale-stays 25 and detachably secured to the forging or casting A.

Many different constructions of stay-bands or securing devices may be employed; but in practice I prefer to employ a flexible band 30 which can be readily encircled around the bale-stays and bale. The particular form of band or securing device shown, to which, however, my invention is not to be limited or restricted, comprises a chain, which, by reason 35 of its flexibility and the ease and facility with which it may be passed around the bale-stays and bale, renders this form of stay-band or securing device particularly desirable. Moreover, by the use of a chain little tendency or 40 liability of the band or securing device to stretch longitudinally is developed. Of course it is obvious that other forms of bands or securing devices may equally well answer the purpose, such as a rope, wire cable, or other 45 form of band.

The band or securing device B may be attached to the forging or casting A in any suitable or convenient manner—as, for instance, by providing in one end of said casting or 50 forging a hook or eyelet a, which affords means of attachment of band B to said forging or casting.

The casting or forging A may be suitably constructed to detachably engage with a bale-stay and also to afford means of attachment of the free end of the band or holding device B thereto after such band or holding device has been passed around the bale and the stay is applied thereto. A simple and convenient 60 construction for attaining these objects is shown in the drawings; but it is to be understood that my invention is not limited or restricted thereto, as changes therein and variations therefrom would readily suggest themselves to persons skilled in the art and still fall within the spirit and scope of my invention. In the particular form shown the forg-

ing or casting A is provided with an enlarged head a', having formed integrally therewith or otherwise suitably secured thereto suitable angular flanges or projections a² a³. The projection or flange a³ is formed into the fingers a⁴, slightly separated from each other to form the space a⁵ therebetween. The flange or projection a² may be formed into a hook to afford means for detachably engaging the forging or casting to a bale-stay, and the flange or projection a³ may afford means for readily attaching the free end of the bale-stay band or securing device B thereto. 80

The operation is as follows: Assuming the press to be in operation and the bale-stays to be carried around or revolved about the bale in the usual manner and in the direction indicated by the arrows in Figs. 2 and 4, now 85 in order to apply the bale-stay band or securing device the hook portion of the forging or casting A is engaged with a bale-stay F in the manner clearly shown in Fig. 2. The continued operation of the press carries the 90 hook around with the bale-stay, the operator allowing the band or securing device B to slip through his hand, at the same time suitably guiding the same around the bale-stays until a complete revolution has been accomplished. 95 At this point the knives, blades, or other suitable devices G of the stays are projected into the compressed column, as shown in Fig. 3, said devices being shown in retracted position in Fig. 1. At the same time the stay-band or securing device is drawn tightly 100 around and is applied in engaging relation with respect to the hook or casting A, as most clearly shown in Fig. 4. In the particular construction shown this application is effected 105 by inserting flatwise one of the links of the chain into the space a⁵ between the fingers a⁴, as clearly shown in Fig. 6. The next adjacent link of the chain, occupying crosswise relation, takes bearing against the inner surface of the flange a³ or the fingers a⁴ thereof, thereby efficiently, but detachably, locking or securing the chain to the hook or casting A. Thus it will be seen that the bale-stays are efficiently locked or held against 110 spreading apart and that the bale-stay band or securing device is applied without arresting the continuous operation of the press. After the bale-stay band has been applied, as 115 described, the detached bale may be removed and the permanent wires or other securing devices applied to the detached bale without danger of undue expansion, the applied bale-stays remaining in position to clamp the detached bale between the knives, blades, or 120 other devices G and the bale-base D until the permanent wires or ties are applied. 125

As above indicated, while a bale-stay band of the character set forth is particularly well adapted for use in connection with continuously-operating presses and may be applied without arresting the operation of the compressing apparatus it is also well adapted for use with other constructions and arrange-

ments of presses and where the press is not continuously operated, for it is obvious that the bale-band may be passed by and around and in encircling relation with respect to the 5 bale-stays and bale.

The bale-stay band or securing device constructed as above described may be readily detached from encircling relation with respect to the bale and bale-stays after the permanent securing bands or ties have been applied to the detached bale in a most simple and expeditious manner by merely detaching the free end of the band B from engaging relation with respect to the head of the casting 15 or forging A and unwinding the band from around the bale and bale-stays and then detaching the hook from the particular stay with which it has been engaged.

It is obvious that many variations and changes in the details of construction and arrangement would readily occur to persons skilled in the art and still fall within the spirit and scope of my invention. I do not desire, therefore, to be limited or restricted to the 25 exact details of arrangement shown and described; but,

Having now set forth the object and nature of my invention and a construction embodying the principles thereof, what I claim as 30 new and useful and of my own invention, and desire to secure by Letters Patent, is—

1. The combination with a bale-stay, of a bale-stay band or securing device, means for detachably connecting one end thereof to said 35 bale-stay the other end arranged to be passed around and in encircling relation with respect to the bale, and means for holding the free end of said band or device in such encircling relation, as and for the purpose set forth.

2. The combination with a bale-stay, of a bale-stay band or securing device, means for detachably connecting the same at one end to said bale-stay, the other end arranged to be passed around in encircling relation with 45 respect to the bale, and means for detachably holding the free end of said band or device in such encircling relation, as and for the purpose set forth.

3. The combination with bale-stays and a hook arranged to be detachably engaged with a bale-stay, of a band or securing device connected at one end to said hook, the other end of said band arranged to be passed around and in encircling relation with respect to the

bale-stays, and means for detachably connecting said band at the free end thereof to said hook, as and for the purpose set forth. 55

4. The combination with bale-stays a casting or forging having a hook, said hook arranged to be detachably engaged with a bale-stay, of a band or securing device connected at one end to said casting or forging the other end thereof arranged to be passed around and in encircling relation with respect to the bale-stays, and means formed on said hook for detachably engaging said band at its free end, as and for the purpose set forth. 60 65

5. The combination with bale-stays and a forging or casting having a flange or projection, adapted to form a hook to detachably engage a bale-stay, of a band or securing device connected at one end to said forging or casting, and means formed on said forging or casting for detachably engaging the other end of said band or securing device, whereby after 70 75 passing around in encircling relation with respect to the bale-stays, said end may be detachably held by said casting or forging, as and for the purpose set forth.

6. The combination with a casting or forging having flanges or projections, one of said flanges or projections forming a hook for detachable engagement with a bale-stay, and the other provided with fingers, of a stay-band or securing device connected at one end 80 85 to said forging or casting, and adapted to be passed around and in encircling relation with respect to the bale-stays, and to be detachably received between said fingers, as and for the purpose set forth. 90

7. A bale-stay-securing device comprising a casting having a hook adapted to detachably engage a bale-stay, a chain connected at one end to said casting the other end of said chain arranged to be passed around and in encircling relation with respect to the bale-stays, said casting provided with fingers arranged to engage the free end of said chain to hold the same in encircling relation, as and for the purpose set forth. 95 100

In witness whereof I have hereunto set my hand, this 11th day of January, 1901, in the presence of the subscribing witnesses.

WATSON M. HOLMES.
